UNITED STATES PATENT OFFICE.

FRANCIS W. DRAPER, OF DETROIT, MICHIGAN, ASSIGNOR TO FARRAND ORGAN COMPANY, OF DETROIT, MICHIGAN, A CORPORATION.

SELF-PLAYING MUSICAL INSTRUMENT.

No. 927,507.

Specification of Letters Patent.

Patented July 13, 1909.

Application filed April 3, 1905. Serial No. 253,547.

To all whom it may concern:

Be it known that I, FRANCIS W. DRAPER, residing at Detroit, in the county of Wayne and State of Michigan, a citizen of the 5 United States, have invented certain new and useful Improvements in Self-Playing Musical Instruments, of which the following is a specification, reference being had therein to the accompanying drawings.

10 The invention relates more particularly to the construction of pianos, adapted for either manual or automatic operation of the string striking action.

It is a primary object of the invention to 15 obtain a construction of automatic action which is capable of being placed within the case of an ordinary manually operated piano without change in the latter, and to this end, the invention consists in the peculiar construction and arrangement of parts as hereinafter set forth.

In the drawings, Figure 1 is a vertical cross section through a piano to which my 20 improvements are applied. Fig. 2 is an enlarged view of a portion of Fig. 1, illustrating the auto-pneumatic action. Fig. 3 is a sectional perspective view of some of the parts of Fig. 2 detached. Fig. 4 is a horizontal view on line α — α Fig. 2.

30 In the manufacture of pianos, it is usual to provide a key supporting bed, which projects forward beyond the lower portion of the case. The purpose of this over-hang is to provide the necessary room for the feet of 35 the player, and bring the pedals in most convenient relation to the keys for easy manipulation. Thus, the player can perform upon the instrument with greater ease than where less room is provided beneath the key bed 40 and the pedals are shifted into some other relation.

Heretofore, in the construction of combined automatic and manually operable pianos, it has been found necessary to provide 45 greater space within the case than with the ordinary piano for the placing of the automatic action, and in certain constructions this additional space has been obtained by shifting the front panel at the lower portion 50 of the case forward and correspondingly shifting forward the pedals. The result is that the instrument is not as well adapted for easy manual operation as the ordinary piano on account of the changed relation between the pedals and the keys and the cramp-

ing of the space for the legs and feet of the player. In the present construction, the automatic action is adapted for placing within the case of the ordinary piano, without either shifting the front panel forward or increasing the width of the case as a whole. Another feature of the construction is that the whole system of pneumatics for the automatic action is arranged beneath the key bed, and the connections to the tracker, which 60 is above the key bed, are formed by tubes passing through the bed between the keys.

As shown, A is the case of a piano of any ordinary construction, B the key bed therefor, C the keys, and D the hammer action 65 operated thereby. Below the key bed is the front panel E of the case, which is the usual distance in rear of the front edge of the bed. This arrangement leaves comparatively a narrow space between the said panel and 70 the harp F of the piano, which is insufficient to receive the entire system of pneumatics for the automatic action, as heretofore constructed. With my construction, I have succeeded in so compactly arranging 75 the several pneumatics of the system that all may be stored within the space above referred to, as well as the pumping and store bellows for supplying wind to the action, 80 the construction being as follows:—

G, G', G², etc., are tiers of power pneumatics for operating the hammer action, the pneumatics of each tier extending almost completely across the space between the front panel E and the harp and being 85 hinged at the ends adjacent to the panel.

H are rods connected to the movable portion of each pneumatic and extending upward in rear of the key bed into proximity to adjustable buttons I depending from the 90 keys, the arrangement being such that the operation of the pneumatics will push upward the rear ends of the keys and through the medium of the latter, actuate the hammer action.

Above each tier of pneumatics G is a wind chest J and associated primary and secondary pneumatics for controlling the respective power pneumatics. In order that both the primary and secondary pneumatics may be arranged within a limited space, they are arranged in adjacent series and are staggered in relation to each other.

In detail, the wind chests J are preferably formed of a bottom section α , upon 100

which the primary and secondary pneumatics are placed, and a top section *b* having mounted therein the primary valves *K* and the secondary valves *L*. The connections between these valves and their respective pneumatics which they control, are formed by channels preferably in the front section *c* and the rear section *d* of the chest and connecting channels formed in the sections *a* and *b*.

The primary and secondary pneumatics are preferably of the pouch type, *i. e.* they are formed by recesses *e*, *f* in the bottom section *a*, which are covered by leather pouches or flexible diaphragms *g*. As has been stated, the primary and secondary pneumatics are arranged in adjacent series and staggered in relation to each other, this arrangement permitting of locating the circular recesses *e*, *f*, in a comparatively narrow space. Thus, the entire width of the chest *J* is only equal to or slightly less than the pneumatics *G*. The valves *K* and *L* are located in cells in the section *b*, so as to be in vertical alinement with the pouches of the primary and secondary pneumatics. Where the structure is formed of wood, the section *b* is preferably formed with its forward portion *b'* of lesser width than its rear portion *b''*. Cells *b³* are then formed by boring and counter-boring the rear portion *b''*, and ports *b⁴* are formed in the forward portion *b'* also by boring. The cells *b³* are connected by cross bores *b⁵* with registering bores in the section *d* which extend to the respective pneumatics *G*. The bores *b⁴* connect with intersecting cross bores *b⁶* extending inward from the front edge of the portion *b'*.

The lower section *a* is bored from its forward edge to alternately intersect with the recesses *e*, *f*, for the primary and secondary valve pouches. These bores *a'* and *a''* communicate with registering bores *c'*, *c''* in the front section *c* of the chest. The bores *c'* connect with tubular conduits *M* leading to the tracker, while the bores *c''* communicate with the bores *b⁶* leading to the bores *b⁴* for the primary valves. As the bores *c''* are in line with the bores *a''* and the latter are in the vertical plane of the cells *b³* for the valves *L* it is evident that they would be out of alinement with the bores *b⁶*, which are in the plane of the ports *b⁴* intermediate the planes of adjacent cells *b³*. Thus, to complete the connection between the bores *b⁶* and *c''*, channels *b⁷* are formed in the front edge of the section *b*, which extend from the bores *b⁶* into registration with the bores *c''*.

With the construction above described, a very compact arrangement of parts is obtained and also one which permits of ready access to the valves when necessary. To this end, the sections *a* and *d* are preferably

united by a grooved joint, so as to be in effect integral and may be permanently mounted within the case, while the sections *b* and *c* are secured by screws and may be easily removed. The offset in the section *b* formed between the portions *b'* and *b''* thereof, permits of arranging securing screws *h*, which extend through the portion *b''* between the cells *b³* and secure the section *b* to the section *d*. The section *c* may also be removably secured by screws passing between the bores *c'* and *c''* and engaging with the sections *a* and *b*.

As illustrated, three tiers of power pneumatics *G*, each provided with the chest *J* as above described, are arranged beneath the key bed and in the space between the front board *E* and the harp of the piano. Beneath these pneumatics is a space for the pumping and store bellows, so that the entire automatic action, with the exception of the tracker and music winding mechanism, is beneath the key bed. The tracker *N* is preferably arranged above the key striking action, so as to avoid any increase in the width of the upper portion of the case. Pneumatic connections are then provided between the tracker and the primary pneumatics formed by the conduits *M* above referred to, and these are arranged to pass downward from the tracker in a plane forward of the hammer action and thence between the keys and through the bed to the respective chests *J*. The connections for the lower chest pass in front of the superposed chests and between the same and the front panel *E*. Thus, the connection is practically the shortest and most direct that can be made between the points of location of the tracker and of the various primary valve.

The operation of the pneumatic action is in the usual manner well known to those skilled in the art. Air passing through the tracker, the conduit *M*, bores *c'* and *a'* operates the pouch pneumatic in recess *e* which raises the valve *K*, allowing atmospheric pressure to pass through bores *b⁴*, *b⁶*, *b⁷*, *c²* and *a²* and lift pneumatic *g* in recess *f*. The pneumatic *g* in turn raises valve *L*, causing the collapse of the power pneumatics *G*.

What I claim as my invention is:—

1. A pneumatic action comprising a wind chest, power pneumatics secured to and beneath the bottom of said chest, primary and secondary pneumatics within said chest mounted on the bottom thereof, superposed primary and secondary valves, a section in which said valves are mounted, forming a detachable top wall of said chest, and connections between said primary valves and secondary pneumatics, and said secondary valves and power pneumatics respectively located in the opposite side walls of said chest.

2. A pneumatic action comprising a wind

- chest, a power pneumatic mounted beneath the bottom of said chest, primary and secondary pneumatics within said chest, primary and secondary valves respectively actuated by said primary and secondary pneumatics, a single detachable top section to said chest in which both of said valves are mounted, a single bottom section in which said pneumatics are mounted, a detachable 10 side wall for said chest having a series of parallel channels therein, recesses in the bottom of said chest connecting respectively with said primary and secondary pneumatics and alternately with the parallel channels, 15 ports in the top wall of the chest connecting said primary valves with the channels leading to said secondary pneumatics, a passage in the other side wall of said chest leading from said secondary valve to said power pneumatic, and connections between the alternate parallel ports and the tracker. 20
3. A pneumatic action comprising a wind chest, primary and secondary pneumatics within said chest, superposed primary and 25 secondary valves mounted in the top section of said chest, a detachable side wall for said chest, having a series of parallel ports therein, ports in the bottom of said chest connecting respectively with said primary and 30 secondary pneumatics and alternately with said parallel ports, ports in the top wall of said chest connecting said primary valves with the ports leading to said secondary pneumatics, and connections between the 35 alternate parallel passages and the tracker.
4. A pneumatic action comprising a wind chest, adjacent series of primary and secondary pneumatics within said chest and staggered in relation to each other, superposed 40 primary and secondary valves, parallel passages in the bottom and side walls of said chest, alined and alternately connecting with said primary and secondary pneumatics, and passages alined with said
- primary valves in the top wall of said chest, 45 having offsets for connecting with the alternate passages in the side wall of said chest, which lead to said secondary pneumatics. 50
5. A pneumatic action comprising a wind chest, a power pneumatic mounted beneath the bottom of said chest, staggered primary and secondary pneumatics within said chest above said power pneumatic, superposed primary and secondary valves mounted in the top wall of said chest, a passage in one 55 side wall of said chest, leading from said secondary valve to said power pneumatic, and passages near the opposite side wall of said chest alternately leading from the tracker connection to said primary pneumatic and from the primary valve to said secondary pneumatic. 60
6. In a pneumatic action, a wind chest comprising a bottom section, a side section permanently attached thereto, a detachable 65 top and second side section, said top section being offset to form portions of different thickness, and having secondary valve cells in the thicker portion and primary valve ports in the thinner portion, said ports and 70 cells being staggered in relation to each other, primary and secondary pneumatics mounted on the bottom section of said chest in alinement with said cells, and ports in the top section, passages in said top, detachable 75 side and bottom of said chest in alinement with said primary and secondary pneumatics, and longitudinal channels in the front edge of said top section for cross-connecting the ports of said primary valve with the passages leading to the secondary pneumatics. 80
- In testimony whereof I affix my signature in presence of two witnesses.
